F. F. BRADLEY

MATTRESS

Filed Oct. 2, 1924

2 Inventor:
Franklin F. Bradley
By H. A. Bissell, Secy.

UNITED STATES PATENT OFFICE.

FRANKLIN F. BRADLEY, OF CHICAGO, ILLINOIS.

MATTRESS.

Application filed October 2, 1924. Serial No. 741,269.

To all whom it may concern:

Be it known that I, FRANKLIN F. BRADLEY, a citizen of the United States, residing at Chicago, in the county of Cook and the 5 State of Illinois, have invented a certain new and useful Improvement in Mattresses, of which the following is a full, clear, concise, and exact description.

My invention relates to mattresses and has 10 a number of advantageous characteristics.

In accordance with one characteristic of 15 my invention, the mattress is made of torso length and a piece of sheet material is connected with the mattress crosswise to be projectable beyond the foot end thereof along the mattress to receive the legs of the occupant. This sheet portion is itself desirably made of foldable material, such as canvas, and is preferably connected with the end of 20 the foot thereof.

In accordance with another characteristic of my invention, an additional sheet portion of foldable material is connected with the mattress, also crosswise, and pillow stuffing 25 is provided at the head end of the mattress over which stuffing this sheet portion is folded to complete the formation of a pillow.

In accordance with another characteristic of my invention, the mattress itself is formed 30 in hinged sections foldable upon each other crosswise of the mattress. The mattress is preferably built of assembled upright readily compressible coiled springs in order that it may be compacted into much reduced 35 space for transportation and storage.

A mattress employing all of the characteristics of my invention is of especial use to campers, as, in addition to being readily compacted into small space for transportation and storage, it will readily adapt itself 40 to irregularities in the ground and to the curvature of the occupant's body.

The invention will be more fully explained in connection with the accompanying drawing 45 in which Fig. 1 is a perspective view of the mattress when folded; Fig. 2 is a perspective view illustrating the mattress unfolded; Fig. 3 is a perspective view illustrating the mattress in use; and Fig. 4 is a longitudinal view of a portion of the mattress.

The mattress illustrated is formed of assembled upright compressible coiled springs 50. These springs are desirably arranged in two equal groups which are in hinged connection crosswise of the mattress at the mid- 55 portion thereof near the mattress top where-

by one mattress section may be folded to lie upon the other to arrange the mattress for shipment or storage. The coiled springs are sufficiently light to enable the folded mattress to be compacted into a small space, although the springs are sufficiently strong to comfortably support the occupant when the mattress is unfolded. The two sections of the mattress are of a length to accommodate 60 the torso of the sleeper, it being found unnecessary to provide any spring support for the sleeper's legs below the hips. The mattress sections are preferably of box-like form, being enclosed within casings 2 of canvas or other suitable material, these casings being joined, as indicated at 3, crosswise of the mattress at the middle and top thereof so that one mattress section may readily be unfolded when the mattress is to be adjusted 70 for use and may readily be folded when the mattress is to be adjusted for shipment or storage. The form of hinge illustrated at 3 is preferred but other hinge formations may be employed.

While it is unnecessary to provide a spring support for the legs of the sleeper, yet some measure of support is desirable, and to this end, I connect a piece of sheet material 4 flexibly with the mattress to project beyond 75 the foot of the same lengthwise of the mattress, in adjusting the mattress for use, or which may be folded up when the mattress is folded.

In the preferred embodiment of the invention, the piece of sheet material 4 is of foldable material, such as canvas, this piece of foldable material being preferably an integral part of a long sheet 5 which overlies the top side of the mattress and is sewed 85 thereto around the border of the mattress, so that the sheet portion 4 becomes assembled with the mattress at the transverse edge of the foot-end thereof.

A second sheet portion 6 of foldable material is connected crosswise with the mattress at the head-end thereof and preferably at the head-end edge. The sheet portion 6 may be temporarily curled or folded about suitable pillow stuffing 7 when the mattress is unfolded and adjusted for use. The sheet portion 6, similarly to the sheet portion 4, is desirably an integral continuation 100 of the main sheet 5. When the mattress is folded, the sheet portions 4 and 6 105 may be disposed as illustrated in Fig. 1, whereafter the folded mattress may be com-

pressed into a shallow box convenient for transportation and storage.

While I prefer to form the mattress in foldable sections, as described, yet the invention is not to be limited to such a construction, in so far as the sheet portions which are added to the head and foot of the mattress are concerned, nor is the mattress to be limited to any particular length 10 in the relation of the sheet extension 6 thereto.

Changes may be made without departing from my invention.

Having thus described my invention, I 15 claim:—

1. A mattress in combination with a sheet portion made of foldable material connected crosswise therewith, and a pillow stuffing at the head end of the mattress over which 20 stuffing said sheet portion is folded to complete the formation of a pillow.

2. A mattress in combination with a sheet portion made of foldable material connected crosswise therewith at one end, and a 25 pillow stuffing at this end of the mattress over which stuffing said sheet portion is folded to complete the formation of a pillow.

3. A mattress formed in hinged sections 30 foldable upon one another crosswise of the mattress in combination with a sheet portion made of foldable material connected crosswise therewith, and pillow stuffing at the head end of the mattress over which

stuffing said sheet portion is folded to complete the formation of a pillow. 35

4. A mattress formed in hinged sections foldable upon one another crosswise of the mattress in combination with a sheet portion made of foldable material connected 40 crosswise therewith at one end thereof, and pillow stuffing at this end of the mattress over which stuffing said sheet portion is folded to complete the formation of a pillow.

5. A mattress formed of assembled upright compressible coiled springs and in hinged sections foldable upon one another crosswise of the mattress in combination with a sheet portion made of foldable material connected crosswise therewith, and 50 pillow stuffing at the head end of the mattress over which stuffing said sheet portion is folded to complete the formation of a pillow.

6. A mattress formed of assembled upright compressible coiled springs and in hinged sections foldable upon one another crosswise of the mattress in combination with a sheet portion made of foldable material connected crosswise therewith at one 55 end thereof, and pillow stuffing at this end of the mattress over which stuffing said sheet portion is folded to complete the formation of a pillow.

In witness whereof, I hereunto subscribe 60 my name.

FRANKLIN F. BRADLEY.
